DOUBLE NECK ELECTRIC GUITAR

Claude L. Deaver, Springfield, Mo., assignor to The Stratosphere Guitar Manufacturing Company, Inc., Springfield, Mo., a corporation of Missouri

Application June 14, 1957, Serial No. 46,600

Term of patent 14 years

(Cl. D56—1)

Fig. 1 is a top plan view of a double neck electric guitar, showing my new design;

Fig. 2 is a side elevational view; and

Fig. 3 is an end elevational view thereof.

I claim:

The ornamental design for a double neck electric guitar, as shown.
